(57) **CLAIM**

I claim the ornamental design for a coffee filter support, as shown and described.

DESCRIPTION

FIG. 1 is a perspective view of a coffee filter support showing my new design;

FIG. 2 is an unrolled top plan view thereof, the bottom plan view being identical thereto;

FIG. 3 is a side elevational view thereof, the opposite side being a mirror image thereof;

FIG. 4 is an end elevational view thereof, the elevational view of the opposing end being identical thereto; and,

FIG. 5 is a reduced perspective view showing the coffee filter support in use.

The broken lines in FIG. 5 are for illustrative purposes only and forms no part of the claimed design.
